JONATHAN LUCAS, OF SAVANNAH, GEORGIA, ASSIGNOR TO LUCAS-LAMBORN LOOM CORPORATION, OF NEW YORK, N. Y., A CORPORATION OF NEW YORK.

SHUTTLE MECHANISM FOR LOOMS.

Application filed May 16, 1925, Serial No. 30,656. Renewed November 1, 1926.

My invention relates to shuttle mechanism for looms and has for its object to provide a mechanism including a pair of inversely reciprocated supporting devices whereby the shuttle is positively carried to and fro through the shed and constructed in a manner to prevent interference or entanglement with the warp threads of yarns comprising the shed and to protect the shuttle against such entanglement. A further object of the invention is to provide a construction in which the shuttle is capable of accommodating a bobbin of large size to thereby increase the yarn carrying capacity to a maximum extent. In addition, the invention contemplates a construction in which the transfer of the shuttle from one supporting device to the other is automatically accomplished with a minimum of friction and in a uniform and positive manner. Other more specific objects will appear from the description hereinafter and the features of novelty will be pointed out in the claims.

In the accompanying drawings, which illustrate an example of the invention without defining its limits, Fig. 1 is a side elevation of the mechanism; Fig. 2 is a fragmentary plan view partly in section; Fig. 3 is a corresponding plan view showing the parts in a different position; Fig. 4 is a plan view of the mechanism and Fig. 5 is a cross-section on the line 5—5 of Fig. 3.

In the drawings, 10 represents a portion of the loom developed to constitute a guiding means extending transversely of the loom and in such relation to the customary shed *b* of warp threads as to permit the shuttle *a* to be passed therethrough in the manner to be more fully set forth hereinafter. A pair of carriers 11 of suitable form and dimensions are mounted slidably upon the guiding means 10 so as to be inversely reciprocable thereon toward and away from each other; the mechanism whereby the inverse reciprocation of the carriers 11 is accomplished may be of any suitable type, such as for instance is shown and described in my copending application Serial No. 711,581 in which case the carriers 11 may be connected with such mechanism by means of links 12. In the illustrated example, the carriers 11 include members 13 which are mounted upon uprights 11^a and project toward each other and are preferably of tubu-

lar construction in order to reduce the dead weight to a minimum and at the same time provide a maximum of strength in said members 13; the outer ends of the latter are preferably bevelled or curved as indicated at 13^a and the outer surfaces of the members 13 are smooth and free from projections of any kind. In the illustrated example, the portions 13^a comprise parts of the uprights 11^a which form units with the members 13.

The shuttle mechanism further comprises supporting devices in the form of rods or fingers 14 and 14^a arranged in cooperating pairs upon the respective carriers 11 and projecting in directions toward each other from the members 13, to which said fingers 14 and 14^a are secured in any conventional manner as by means of screws 15. In the preferred arrangement, the fingers of each pair are located above each other although not necessarily in line; thus, as shown in Fig. 5, the fingers 14^a constituting one pair are located in spaced vertical registry with each other while the fingers 14 comprising the other pair are spaced apart vertically but are not in vertical registry with each other. This arrangement is followed in the illustrated example simply to provide operative space for other parts of the mechanism and may be changed to meet other existing conditions. In any case the position of the pair of fingers 14 on its carrier member 13 is off-set with respect to the positions occupied by the pair of fingers 14^a on its carrier member 13 so that the fingers of one carrier are out of line with the fingers of the other carrier as shown by way of example in the drawings, the purpose of which will be pointed out clearly further on in the description.

With the construction set forth, the shuttle *a* is provided with means arranged to cooperate with the aforesaid fingers 14 and 14^a to establish a supporting relation alternately with each pair of fingers whereby the shuttle *a* is carried alternately by each carrier 11 and transferred thereby through a portion of the warp shed *b*; it will be understood that the reciprocating movements of the carriers are such that the shuttle *a* will be carried thereby, back and forth through the warp shed *b* to lay the filler threads. In the illustrated example, the shuttle *a* is provided accordingly with

grooves 16 and 16^a located upon its upper and lower faces, or upon those faces which lie contiguous to the paths of travel of the aforesaid fingers 14 and 14^a, and extending lengthwise thereof as shown in Figs. 2 and 3. The axial length of the lower fingers of each pair 14 and 14^a and preferably of the upper fingers also, with respect to the axial length of the shuttle *a* and of the grooves 16 and 16^a is such that when in operative carrying position in said grooves the fingers of each pair will extend, in their projecting directions, beyond the transverse centre of the shuttle *a* as shown in Figs. 2 and 3. In this way the shuttle *a* is supported positively by both pairs of fingers alternately, at a fixed level and is always fixed positively against tilting out of its path of travel. In the preferred construction, the grooves 16 and 16^a taper lengthwise from their entrance ends and the fingers 14 and 14^a are tapered correspondingly as shown in Figs. 2 and 3; as a result of this arrangement the fingers will contact with the walls of the grooves only at a point approximating the completion of the connection between the shuttle and the fingers and prior to such completion, will be out of contact with such walls; similarly as the fingers are withdrawn from said grooves, disengagement between the walls of the latter and said fingers takes place almost immediately. Thus only a minimum of friction is developed between the fingers and the grooves as the transfer from one carrier to the other takes place and a practically rubbing action between the walls of the grooves and the fingers and along the same is eliminated.

For the purpose of locking the shuttle *a* alternately upon each pair of fingers 14 and 14^a or in other words upon the respective carriers 11, latching levers 17 and 17^a may be connected pivotally at 18 with the carrier members 13 so as to be movable in horizontal planes as shown in Figs. 2 and 3. At their free ends these levers 17 and 17^a are provided with inclined surfaces 19 and 19^a respectively and with hooks 19^b and 19^c adapted to cooperate respectively with lugs 20 and 20^a located rigidly upon the shuttle *a* at the proper points. Normally, the hooks 19 and 19^a rest in such position that as the carrier members approach each other, the one or the other of said hooks will ride up on a flange 21 extending lengthwise of the shuttle, said hooks being maintained in and returned to said normal position by means of leaf springs 22 fixed upon the carrier members 13 and having their free ends in engagement with the levers 17 and 17^a; the extent to which the springs 22 can move the levers 17 and 17^a is limited by the engagement of lugs 14^b on said levers with some fixed portions of the carrier members 13; the lugs 20 and 20^a are of such dimensions

that the one or the other of the inclined surfaces 19 or 19^a, when the hook 19^b or 19^c is in engagement with the lug 20 or 20^a, as the case may be, will be located outwardly beyond the path travelled by the free end of the other lever as shown in Fig. 2. With this arrangement, the free end of the one lever will be projected beneath the free end of the other lever, as the carriers approach their innermost positions, and by co-action with one or the other of the inclined surfaces 19 or 19^a will disconnect one hook automatically from its lug and at the same time connect the other hook automatically with the other lug. In this way, the shuttle *a* is so locked automatically upon the supporting devices 14 and 14^a alternately to effect the transfer of the shuttle *a* from one carrier to the other.

As shown in the drawings, the novel carrier construction permits the shuttle *a* to be made of relatively large dimensions and capable of supporting a bobbin 23 of much greater size than is possible with existing shuttles; thus the present shuttle *a* is enabled to carry a maximum supply of filler thread *c* from which it follows that stoppage of the loom to permit replenishment of such supply occurs to a much lesser degree than in looms in which the warp thread carrying capacity is less. The filler thread *c* passes from the bobbin 23 through an aperture 24 formed in the one end of the shuttle *a* as shown in Fig. 1 and is maintained under a tension sufficient to prevent unintentional unwinding of the bobbin 23, by means of a tension device 25; the latter, as shown in Figs. 1 and 5, comprises a lever consisting of a continuous wire bent into U-shape and tapered to form an angle 26 in which the thread *b* is seated, the free ends of the wire being fixed pivotally in the shuttle in any convenient manner to permit the angle 26 to bear against the thread *c* as shown in Figs. 1 and 5 and to hold the latter by the gravitational weight of the device 25.

To prevent positively interference and entanglement with the warp threads of the shed, even if said threads or any of them should sag or become broken, shields 27 are provided which project from the respective carrier members 13 in parallel relation to the axes of the fingers 14 and 14^a as shown in the drawings. The shields 27 extend beyond the free ends of the fingers 14 and 14^a respectively and terminate preferably in tapered ends 28 as shown in Fig. 1, said shields 27 being continued in the form of guards 29 which, as shown in Figs. 4 and 5, cover and enclose the fingers 14 and 14^a; the guards 29 merge into the tapered end 28 of the shields 27 and into the carrier members 13 along sloping lines 30 as shown in Fig. 4 so that abrupt edges in the direction of the travel of the carriers on which the filler

thread *c* may become caught are avoided entirely. The shield of one carrier is off-set with respect to the shield of the other carrier while the top guards 29 are cut away and arranged to overlap each other longitudinally and transversely in stepped relation in the innermost position of the carriers, as illustrated in Figs. 4 and 5. For the purpose of strengthening the construction and in particular to prevent vibration in the fingers 14 and 14^a, the latter may be attached to the guards 29, for instance by rivets 31 or the like as shown in Fig. 5.

Assuming the shuttle *a* is being supported by the fingers 14, the hook 19^b will be in engagement with the lug 20 and the lever 17 will be pressed against the latter by its spring 22. At the same time, the hook 19^c is pressed, by its spring 22, towards the upper finger 14^a. In the operation of the loom the carriers 11 will move finally toward each other in the directions indicated by the arrows *d* in Fig. 2 and will approach gradually their innermost positions, the shuttle *a* at this time being carried by the fingers 14 of the carrier 11. In this way, the innermost position is approached and the fingers 14^a will finally enter the grooves 16^a and travel lengthwise thereof to the final innermost position of the parts. It will be seen, by reference to Fig. 2, that the fingers 14^a do not contact with the walls of the grooves 16^a even though the final innermost position has almost been reached, this being due to the tapered form of the fingers and the grooves as hereinbefore set forth. As the aforesaid innermost position is approached, the inclined surface 19^a, by engagement with the flange 21 and because of continued movement in the direction of the arrows *d* will cause the hook 19^c to ride up on the flange 21 against the tension of the one spring 22. This will finally bring the free end of the lever 17^a into engagement with the inclined surface 19 of the lever 17 as shown approximately in Fig. 2 and as operation of the mechanism continues will exert a shifting action upon said surface 19 against the tension of the cooperating spring 22 and thereby move the hook 19^b out of engagement with the lug 20. This will cause the hook 19^b to ride upon the lever 17^a at its free end, the hook 19^c being snapped finally into engagement with the lug 20^a as soon as the latter has been passed, the position of the parts at this stage being as indicated in Fig. 3.

The shuttle *a* is now disconnected from the right hand carrier 11 and connected with the left hand carrier 11 in Fig. 1, the fingers 14^a being, at the same time, seated fully in the grooves 16^a. Continued actuation of the mechanism now causes the carriers to move away from each other in the directions indicated by the arrows *e* in Fig.

3, the shuttle *a* being carried to the left and passed through the shed *c* in this direction and then back again to the right to the meeting point where it is transferred back to the fingers 14, disconnection of the hook 19^c from its lug 20^a being effected by the action of the lever 17 and inclined surface 19 in the manner set forth previously. From this point, the movement of the shuttle to the right is continued because it is now carried by the fingers 14 and because the carriers 11 are moved away from each other again. By the reciprocation of the carriers toward and away from each other and the automatic transfer of the shuttle from one set of fingers to the other, the shuttle *a* is carried positively back and forth through the shed *b* to lay the filler threads *c* which are packed by the beater in the well known way.

As the carriers travel into the shed, the tapered ends 28 of the guards 27 and the sloping edges 30 of the shields 29 are always presented first to the opposite entrances thereof; as the carriers move backwardly out of the shed, the bevelled or curved portions 13^a constitute the advancing ends. Should the shed or any of the threads thereof sag for any reason, these ends 28 and edges 30 and the portions 13^a will cam said threads aside and thus will prevent the same from becoming entangled with the shuttle mechanism or any part thereof. In the innermost position of the parts, the shields 27 and guard 29 of one carrier overlap the corresponding elements of the other carrier, so that the shuttle *a* and associated elements, such as the fingers 14 and 14^a are enclosed almost completely as shown in Fig. 4 and interference with the shuttle during its transfer from one carrier to the other is therefore prevented positively, in other words the shields and guards of the carriers constitute protecting devices which, in the aforesaid innermost position of the parts co-operate to enclose the shuttle and its associated elements.

With the arrangement set forth, a supporting relation is established with each pair of fingers and the shuttle whereby the latter is supported positively at a fixed level against tilting out of its path of travel. Thus absolute axial registry between each pair of fingers and the cooperating grooves of the shuttle is maintained so that the shuttle may be reciprocated through the shed at high speed without danger of clashing with cooperating parts and without interference with the transfer from one carrier to the other. At the same time, the filler thread *c* as it passes through the aperture 24 of the shuttle is held under the desired tension by the weight of the lever 25.

Various changes in the specific form shown and described may be made within

the scope of the claims without departing from the spirit of my invention.

I claim:

1. In a loom, the combination of a shuttle, 5 a pair of carriers arranged to be reciprocated toward and away from each other, supporting devices on said carriers for supporting the shuttle alternately on each of said carriers, the devices of each carrier being off-set with respect to the devices of the other carrier and having operative supporting ranges extending over major portions of the axial length of said shuttle whereby the latter is supported at a fixed level against 15 tilting out of its path of travel, transferring means whereby said shuttle is automatically transferred from the supporting devices of one carrier to the supporting devices of the other carrier and vice versa at said meeting 20 point, and shielding means extending over and beyond said supporting devices in the directions of travel and enclosing said transferring means whereby entanglement with the threads of the shed is prevented.
2. In a loom, the combination of a shuttle, 25 a pair of carriers arranged to be reciprocated toward and away from each other, supporting fingers projecting toward each other on said carriers in cooperating pairs, means on said shuttle adapted to establish a supporting relation alternately with each pair of fingers, the latter having operative lengths extending over major portions of the axial length of said shuttle whereby the latter is supported at a fixed level against 30 tilting out of its path of travel, each pair of fingers being off-set with respect to and capable of overlapping the other pair when said carriers are at their innermost positions, locking levers whereby said shuttle is automatically transferred from the fingers of one carrier to the fingers of the other carrier, and locked thereon, said levers being releasable one by the other and shielding 35 means extending over and beyond said fingers in the directions of travel and enclosing said levers whereby entanglement with the threads of the shed is prevented.
3. In a loom, the combination of a shuttle 40 having grooves extending lengthwise of the upper and lower faces thereof in off-set pairs, a pair of carriers arranged to be reciprocated toward and away from each other, fingers on said carriers arranged in cooperating pairs, each pair being off-set with respect to the other pair and being arranged to enter the cooperating shuttle 45 grooves for supporting said shuttle alternately on said carriers, said fingers having axial lengths sufficient to cause them to project into said grooves beyond the transverse centers thereof whereby said shuttle is supported at a fixed level against tilting out of its path of travel, locking levers whereby 50 said shuttle is automatically transferred from one carrier to the other and vice versa and shielding means extending over and beyond each pair of fingers in the directions of travel and over the latching members and lugs to enclose the same whereby entanglement with the threads of the shed is prevented.
4. In a loom, the combination of a shuttle 55 having grooves extending lengthwise thereof in off-set pairs, said grooves tapering lengthwise from their entrance ends, a pair of carriers arranged to be reciprocated toward and away from each other, 60 fingers tapered to correspond to the taper of said grooves and arranged on said carriers in cooperating pairs, each pair being off-set with respect to the other pair for entrance into the cooperating grooves of said shuttle for supporting the latter alternately on said carriers, said fingers having axial lengths sufficient to cause them to project into said grooves beyond the transverse centers thereof whereby said shuttle is supported at a fixed level against tilting out of its path of travel and transferring means whereby said shuttle is automatically transferred from the fingers of one carrier to the fingers 65 of the other carrier and vice versa.

from the fingers of one carrier to the fingers of the other carrier and vice versa, guards extending lengthwise of and beyond each pair of fingers in the directions of travel and shields combined with said guards and enclosing each pair of fingers and the co-operating locking levers whereby entanglement with the threads of the shed is prevented.

4. In a loom, the combination of a shuttle 70 having grooves extending lengthwise thereof in off-set pairs, said grooves tapering lengthwise from their entrance ends, a pair of carriers arranged to be reciprocated toward and away from each other, 75 fingers tapered to correspond to the taper of said grooves and arranged on said carriers in cooperating pairs, each pair being off-set with respect to the other pair for entrance into the cooperating grooves of said shuttle for supporting the latter alternately on said carriers, said fingers having axial lengths sufficient to cause them to project into said grooves beyond the transverse centers thereof whereby said shuttle is supported at a fixed level against tilting out of its path of travel and transferring means whereby said shuttle is automatically transferred from the fingers of one carrier to the fingers 80 of the other carrier and vice versa.

5. In a loom, the combination of a shuttle 85 having grooves extending lengthwise thereof in off-set pairs, a pair of carriers arranged to be reciprocated toward and away from each other, fingers on said carriers arranged in cooperating pairs, each pair being off-set with respect to the other pair and being arranged to enter the cooperating shuttle 90 grooves for supporting said shuttle alternately on said carriers, said fingers having axial lengths sufficient to cause them to project into said grooves beyond the transverse centers thereof whereby said shuttle is supported at a fixed level against tilting out of its path of travel, lugs fixed on said shuttle, 95 latching members adapted to alternately engage said lugs and to be operated one by the other and released from said lugs whereby said shuttle is automatically transferred 100 from one carrier to the other and vice versa and shielding means extending over and beyond each pair of fingers in the directions of travel and over the latching members and lugs to enclose the same whereby entanglement with the threads of the shed is prevented.

6. In a loom, the combination of a shuttle 105 having grooves extending lengthwise of the upper and lower faces thereof in off-set pairs, a pair of carriers arranged to be reciprocated toward and away from each other, fingers on said carriers arranged in cooperating vertical pairs, each pair being off-set with respect to the other pair and being arranged to enter the cooperating shuttle 110

grooves for supporting said shuttle alternately on said carriers, said fingers having axial lengths sufficient to cause them to project into said grooves beyond the transverse centers thereof whereby said shuttle is supported at a fixed level against tilting out of its path of travel, lugs fixed on the upper face of said shuttle, between the grooves thereon, latching members pivotally mounted to move in horizontal planes and adapted to alternately engage said lugs and to be operated one by the other and released from said lugs whereby said shuttle is automatically transferred from one carrier to the other and vice versa, springs whereby said latching members are maintained in and returned to their operative positions, and shielding means covering said fingers and latching members and extending beyond the same in the directions of the travel to prevent entanglement with the warp threads.

7. In a loom, the combination of a shuttle, a pair of carriers movable toward and away from each other and arranged to receive and support said shuttle in alternate sequence and a shielding device supported on each carrier and arranged to extend lengthwise of and transversely over the shuttle when the latter is carried thereby, the shielding device of one carrier being out of line with the device of the other carrier and adapted to overlap the same when the carriers are in their innermost position whereby said shuttle is enclosed by said shielding devices during its transfer from one carrier to the other.

8. In a loom, the combination of a shuttle, a pair of carriers movable toward and away from each other, fingers projecting in pairs from each carrier for supporting the shuttle in alternate sequence, guards attached to the fingers of each carrier and extending transversely over the shuttle when the latter is in position thereon and a shield connecting the guards of each carrier and extending lengthwise of the shuttle along one side thereof when said shuttle is in position on a given carrier.

9. In a loom, the combination of a shuttle, a pair of carriers movable toward and away from each other, uprights mounted upon the carriers, a member projecting from each upright, and forming therewith a unit, the outer end of which is rounded, the members extending toward each other and having their outer surfaces free from projections, fingers projecting in pairs from the free ends of said members for supporting the shuttle in alternate sequence, and combined shields and guards carried by said members and extending lengthwise and transversely over the shuttle when the latter is supported on a given carrier.

10. In a loom, the combination of a shuttle, a pair of carriers movable toward and away from each other, uprights mounted upon the carriers, a member projecting from each upright, and forming therewith a unit, the outer end of which is rounded, the members extending toward each other and having their outer surfaces free from projections, fingers projecting in pairs from the free ends of said members for supporting the shuttle in alternate sequence, and combined shields and guards carried by said members and extending lengthwise and transversely over the shuttle when the latter is supported on a given carrier, the free ends of the shields being tapered and the fingers, shield, and guard of one carrier being out of line with the fingers, shield and guard of the other carrier.

11. In the loom, the combination of a shuttle, carriers movable toward and away from each other, supporting devices on said carrier for supporting said shuttle in alternate sequence and protecting devices mounted upon said carriers and projecting inwardly therefrom, said protecting devices in the innermost position of the carriers, cooperating to form a protecting enclosure for the shuttle and the supporting devices.

In testimony whereof I have hereunto set my hand.

JONATHAN LUCAS.
